J. J. O'BRIEN

TOOL FOR REMOVING TIRES

Filed Nov. 13, 1920

Inventor
John J. O'Brien

By *Clifford Bradford*

Attorney

UNITED STATES PATENT OFFICE.

JOHN J. O'BRIEN, OF LEESBURG, FLORIDA.

TOOL FOR REMOVING TIRES.

Application filed November 13, 1920. Serial No. 423,880.

To all whom it may concern:

Be it known that I, JOHN J. O'BRIEN, a citizen of the United States, residing at Leesburg, in the county of Lake and State 5 of Florida, have invented certain new and useful Improvements in Tools for Removing Tires, of which the following is a specification.

My said invention relates to tools for 10 collapsing and restoring split rims in the operation of removing tires from and replacing them upon demountable rims and it consists in the construction and arrangement of the tool and attaching devices 15 whereby such work may be performed very quickly and by which the rim may be reassembled very quickly. The tool also embodies a number of other features which make it useful for various other purposes as 20 a general automobile accessory, all as will be hereinafter more fully described and claimed.

Referring to the accompanying drawings, which are made a part hereof and on which 25 similar reference characters indicate similar parts,

Figure 1 is a view partly in section and partly in elevation showing a portion of an automobile rim of the character described 30 with one of my tools connected thereto in the position it occupies just as the operation of removing the tire is to take place,

Figure 2, a view of the tool separately in elevation, and

Figures 3, 4, 5, and 6, detail views.

In said drawings the portions marked A represent the demountable rim and B a tire thereon, both of which parts are or may be of any appropriate construction. The 40 rim A is divided as at point 10 and has a locking device 11 of a common type, or any appropriate type, one part of the rim having an overlapping tongue with a lug 12 adapted to engage with a perforation in the 45 other part as is usual.

The tool comprises a central member or handle 15 longitudinally perforated, one end of the perforation being screw-threaded, it is also transversely perforated the transverse perforation cutting through the longitudinal perforation. A shoulder is formed at point 16 and a shank 17 with a head 18 on one end and an engaging hook 19 upon the other is mounted in said perforation, the 55 head 18 being adapted to abut against shoulder 16. Another shank 20 with a screw-

threaded section 21 is mounted in the screw-threaded end of perforation in member 15 and is formed with an engaging hood 22 on its outer end similar to the hook 19 on the outer end of shank 17. It will be noted that the outer faces of such hook-shaped ends are slightly curved. This is to provide for a free rocking movement between the engaging parts during operation and avoid all binding or strain.

Engaging plates 23 and 24 are secured to the inner face of the rim A, plate 23 being secured at a point near to the split 10 in the rim and plate 24 at a point a considerable distance away from and on the opposite side of said split. Said plates 23 and 24 are duplicates, the construction being shown most clearly in Figure 4. It will be noted that they are formed with a cut-out portion in 75 one edge, the lips of which are tapered toward each other, that is, the recess is of a dove-tailed form and open at one side.

As is well understood, the locking device 11 for securing the two ends of the rim together causes a projection on the interior surface of the rim A and lugs 25 of corresponding thickness are positioned on the interior of said rim at intervals to support it uniformly on the felloe of the wheel. The 80 plates 23 and 24 are made of corresponding thickness and thus lay in the space between the wheel felloes (indicated by dotted line 50) and the tire holding rim, when the parts are assembled.

A handle 26 is mounted in the transverse perforation in the member 15 by which additional leverage may be acquired in the operation of the tool, and an abutment furnished to limit the longitudinal movement 95 of shank 17 when the parts are in place. Said handle 26 is preferably made as a tool in itself having an enlarged end in which a rectangular socket 27 is formed to adapt the same to be used as a wrench and its other 100 end 28 is formed as a screw-driver or prying tool. A tongue 29 is formed on one side of said handle 26 adapted to engage with a groove in the side of the perforation in the member 15 to lock the handle from rotary 105 motion therein. If desired a series of such handles formed as wrenches may be provided, thus providing a wrench for different sized nuts. It will be understood that in the use of the device as a wrench either 110 shank 17 or 20 may be used as a handle to secure additional leverage.

When it is desired to move a nut at a point where the wrench will not reach, when assembled, as shown at Figure 1, the handle 26 may be inserted in the perforation provided for shank 17, the tongue 29 engaging with a groove in the side of said perforation to prevent its independent rotation, and the tool thus utilized as a wrench in the form shown in Figure 5.

10 In operation, it being desired to remove a tire, the rim is removed from the wheel in the well known manner; the plates 23 and 24 are then exposed; the hooks 19 and 22 are then adjusted in the recess of plates 23 and 24 and member 15 is turned to contract the tool or shorten the connection between said plates as indicated by the arrows in dotted lines. Plate 23 being attached close to joint 10 the strain upon the end of the 15 rim to which plate 23 is attached is substantially in an inward direction tending to slide said end along the end of the other part to open joint 10, or until it is free from the adjacent end of said rim, when two parts 20 will slide into an overlapped position, as shown in Figure 6, enabling the tire to be readily removed. After a tire has been adjusted on the rim, by reversing the motion of member 15 the end of the rim bearing 25 plate 23 is forced outward, as indicated by the arrow in whole lines, and as soon as it reaches the position where the ends will pass each other it snaps into place, when the locking plate 11 may again be engaged and 30 the rim be in condition to be replaced on the wheel.

By this means a tire may be removed very quickly and the rim may be restored to its closed position very quickly after a tire has 40 been placed thereon. A tool is also provided which is very useful for many other purposes and desirable to have in the tool box of an automobile and one that when disassembled occupies but little space.

45 Having thus fully described my said invention, what I claim as new and desire to secure by Letters Patent, is:

1. A tool for collapsing split rims comprising a member having intersecting longitudinal and transverse perforations, a portion of said longitudinal perforation being threaded, a shank threaded at its inner end for engagement with the said threaded portion of the longitudinal perforation and

having its outer end formed with a notched portion for engagement with a rim, a second shank carried by the said member having its outer end formed similar to that of the first said shank and a handle adapted to be inserted in the transverse perforation, said handle adapted to serve as an abutment for the said second shank, substantially as set forth.

2. A rim tool comprising a pair of rods, means for moving said rods longitudinally in opposite directions, the outer ends of the rods having notched portions adapted to enter laterally into corresponding cavities in a rim, and said notched portions lying within the cross-sectional periphery of the respective rods, substantially as set forth.

3. Rim operating means comprising a pair of plates for securing to a rim, each plate having a recess entering from one edge and wider at one face of the plate than at the other, in combination with a pair of rods and means for moving them toward and from each other, the outer ends of said rods being shaped to form heads insertable laterally in the said recesses and interlocking with said plates, substantially as set forth.

4. Rim operating means comprising a pair of plates for securing to a rim, each plate having a recess entering from one edge, in combination with a pair of rods and means for moving them toward and from each other, the outer ends of said rods being shaped to form heads insertable laterally in the said recesses and interlocking with said plates, substantially as set forth.

5. Rim operating means comprising plates for securing to a rim, providing a recess on each side of the break in the rim in combination with a pair of rods and means for moving them toward and from each other, the outer ends of said rods being shaped to form heads insertable laterally in the said recesses and interlocking with said plates, substantially as set forth.

In witness whereof I have hereunto set my hand and seal at Washington, District of Columbia, this 12th day of November, A. D. nineteen hundred and twenty.

JOHN J. O'BRIEN. [L. s.]
